HARRY A. INMAN, OF NEWARK, NEW YORK, ASSIGNOR TO BLOOMER BROS. COMPANY, OF NEWARK, NEW YORK, A CORPORATION OF NEW YORK

CONTAINER FOR FRAGILE ARTICLES

Application filed April 17, 1930. Serial No. 444,910.

- This invention relates to a container for fragile articles such for example as eggs. An object of the invention is to provide a generally improved and more satisfactory container having provisions for cushioning the articles placed therein to lessen the danger of breakage both when the articles are being packed originally in the container and while they are being transported.
- 10 A further object is the provision of a container having cushioning means which aids in stiffening the container to prevent accidental crushing thereof.
- 15 Still another object is the provision of a container which eliminates the necessity of using a cushioning table for filling the container with eggs or the like, and which likewise eliminates the necessity of a cushion in a crate filled with such containers.
- 20 A further object of the invention is the provision of a container having satisfactory cushioning means so designed and arranged that the entire container and cushioning means may be manufactured and assembled 25 for transportation substantially entirely by automatic machinery.

To these and other ends the invention resides in certain improvements and combinations of parts, all as will be hereinafter more 30 fully described, the novel features being pointed out in the claims at the end of the specification.

In the drawing:

Fig. 1 is a plan of a container constructed 35 according to a preferred embodiment of the present invention with the cover in open position and partially broken away;

Fig. 2 is a vertical section taken transversely through the container with the cover in closed position;

Fig. 3 is an end view of the filler or partition structure removed from the container and partially collapsed;

Fig. 4 is a side view of the same in collapsed position; and

Fig. 5 is a view similar to Fig. 2 showing a slightly modified form of construction.

Similar reference numerals throughout the several views indicate the same parts.

The novel and improved container of the present invention comprises a body having a bottom 10, sides 11, ends 12, and a cover 13, preferably all formed integrally from a single piece of cardboard or the like suitably folded and pasted in known manner. The cover 50 55 13 has a flap 14 arranged to be inserted inside the front wall 11 when the cover is closed, as plainly shown in Fig. 2 of the drawing.

This body receives a removable filler or partition structure comprising an intermediate longitudinal partition member 15, another longitudinal partition member 16 on one side of the intermediate member 15, and another longitudinal partition member 17 on the opposite side of the intermediate member. 60 65 These three longitudinal partition members preferably lie in substantially vertical planes and are substantially parallel to each other, being spaced a substantial distance from each other to provide article receiving spaces between them. 70

The filler comprises also a plurality of transverse partition members 18 which extend across the longitudinal members 15, 16, and 17 and which sub-divide the space between these members into a plurality of separate compartments, each adapted to receive preferably a single article such as an egg. The longitudinal members and transverse members are suitably slotted where they cross 75 80 each other to permit such crossing, as indicated diagrammatically in the drawing, the exact details of the slots or connections between the members forming no part of the present invention. 85

When the filler or partition structure is removed from the body, it may be collapsed to occupy a relatively thin space by moving the members 15, 16, and 17 longitudinally 90 with respect to each other and transversely

toward each other, so that the transverse partition members 18 are swung around from a position substantially perpendicular to the partition members 15, 16, and 17 to a position substantially parallel to these latter members, as will be clearly understood by those skilled in the art. The slot connections between the members 18 and the members 15, 16 and 17 permit a swinging movement of the transverse partitions relative to the longitudinal partitions and thus allow the filler or partition structure to be collapsed readily and to be expanded again easily when it is desired to insert the partition structure in the body 15 of the container.

A container of the general type so far described, having a body and a filler or partition structure within the body, is in general of known form. Such containers are found 20 in use to be unsatisfactory in some respects. For example, when used for eggs, each egg must be placed comparatively gently in its compartment, otherwise it may strike with considerable force against the flat bottom 10 25 of the container and if this bottom is resting upon a solid unyielding surface, the end of the egg may be cracked. Hence it is necessary in practice to provide a cushion on the top of the table on which the containers rest 30 while the eggs are being packed, in order to enable the eggs to be placed comparatively rapidly in the containers without cracking them. Likewise, when eggs are shipped in such containers in the usual form in crates 35 each holding a number of containers, it is necessary to provide cushioning elements in the crates so that the jars which occur in transportation will not break the eggs.

The present invention provides cushioning 40 means which is self contained in each container and which obviates the use both of a cushion on the packing table and of a cushion in a shipping crate. When containers constructed in accordance with the present invention are being packed, they may be placed directly upon an ordinary table or any other hard surface, and yet eggs or other fragile articles may be packed rapidly in the container without any substantial danger of 45 breakage. Likewise the containers of the present invention may be placed solidly in a crate without the use of a cushioning element at the bottom of the crate as has been customary heretofore.

50 The cushioning means according to the present invention comprises a cushioning element underlying the eggs in such position as to support the eggs resiliently above the bottom 10 of the body. This cushioning element is so designed that it does not interfere with the collapsing of the filler or partition structure into a comparatively thin space.

According to a preferred embodiment of 55 the invention, the cushioning element comprises a V-shaped structure of cardboard or

the like extending along the space between two partition members. As best shown in Fig. 2, one V-shaped cushioning element is preferably used in the space between each two longitudinal partition members, and 60 since there are two such spaces in the container here illustrated, two such cushioning elements are employed, one between the partitions 15 and 16, and the other between the partitions 15 and 17. Each cushioning element has one inclined side 20 and another inclined side 21 preferably made from a single integral piece of cardboard scored at 22 to form a hinge or joint at this point. The bottom of the V-shaped cushioning element, along the line 22, rests substantially 65 upon the bottom 10 of the body, while the edges of the cushioning element are suitably supported at a higher elevation so that this V-shaped construction provides a somewhat 70 resilient cushioning element for supporting eggs 23. When the partition members on either side of the cushioning element move toward each other during collapsing of the structure, the cushioning element may fold 75 up about the score line 22 as a hinge. The cushioning elements are shown partially collapsed in Fig. 3, which plainly illustrates the manner of collapsing.

These cushioning elements may be arranged in any desired manner in the container, but preferably they extend longitudinally of the container in the spaces between the longitudinal partition members 15, 16, and 17, as has already been mentioned. Thus 80 two cushioning elements are provided, one for the row of compartments between the members 15 and 16, and the other for the row of compartments between the members 15 and 17, each cushioning element preferably 85 extending throughout substantially the entire length of the container. As shown in Fig. 1, when the filler is placed within the box body, the ends of the members 20 and 21 of the V-shaped cushioning elements are substantially 90 in contact with the ends 12 of the body, and thus act as columns strengthening the body and tending to prevent inward collapse or crushing of the ends.

One edge of each cushioning element is 95 preferably affixed to one of the partition members, so that the cushioning elements will be at all times secured to the partition structure and may be handled as a unit 100 therewith. The opposite edge of each cushioning element lies substantially in contact with another partition member, but cannot be fixed thereto because the partition members move longitudinally relative to each 105 other during the collapsing of the partition structure, and if both edges of the cushioning elements were fixed to the adjacent partition members, this relatively longitudinal movement would be prevented and the partition 110

structure could not be collapsed in the desired manner.

At present it is preferred to fix the cushioning elements to the intermediate partition member 15 and to have the outer edges of the cushioning elements in contact with but free from the outer partition members 16 and 17. Obviously the cushioning elements could be fixed to members 16 and 17 and free from the intermediate member 15, if desired, but the affixing of the cushioning elements to the intermediate member has a considerable advantage in that the weight on the two sides of the partition member to which the cushioning elements are secured is thus balanced and there is no tendency for the weight of the cushioning elements to bend or deform the bottom edge of the partition member 15 to which they are attached.

In order to secure the cushioning elements to the member 15, each element is preferably provided with a flap 25 attached integrally to the inclined portion 21 and hingedly connected thereto by a score line 26. These flaps 25 extend downwardly along the sides of the lower portion of the intermediate partition 15, as plainly shown in Fig. 2, and are secured to the member 15 in any suitable manner such as by adhesive. The two cushioning elements and their attaching flaps 25 may be separate from each other, though preferably they are both formed of a single piece of material centrally scored and bent around the bottom end of the partition 15 as at 27.

For supporting the extreme edges of the inclined portions 20 of the cushioning elements, while leaving them free of and unattached to partitions 16 and 17, flaps 30 are provided similar to flaps 25, the flaps 30 being preferably integral with the portions 20 and hinged thereto by score lines 31. These flaps 30 when in normal position within the container extend downwardly along side the partition members 16 and 17, as shown in Fig. 2, and the bottom edges of the flaps rest upon the bottom 10 of the container body. Thus these flaps serve to maintain the upper edges of the oblique portions 20 in proper position. It will be seen from Fig. 2 that the oblique portions 20 and 21 together with the flaps 25 and 30 of each cushioning element form roughly the outline of a letter M, and thus the cushioning elements may be described as M-shaped.

From the above description it will be seen that in the preferred construction, the flaps and portions 20, 21, 25 and 30 of both cushioning elements are preferably all made integrally from a single piece of cardboard or the like suitably scored at 22, 26, 27, and 31. It is found in practice that the cutting and scoring of such a cushioning member or pair of cushioning members may be done quickly and easily entirely by automatic machin-

ery, and may be adhesively affixed to the partition member 15 also by machinery. Likewise the partition members may be assembled in proper position relative to each other by machinery and may be collapsed and counted ready for the shipment of the containers in knocked-down condition. The container bodies may be collapsed in known manner, when the fillers or partitions are removed, by the use of suitable known score lines 75 formed in the front wall 11 and end walls 12 of the body. Thus the entire container may be shipped in compact knocked-down form to the place where it is to be used, and then when the packer is ready to place the eggs 80 or other articles therein, he may open up or erect the body, open up a filler, and place the filler in the body. The opening of the filler and placing of it in the body automatically positions the cushioning elements in their proper place, since the resiliency of the cardboard from which the cushioning elements are constructed makes them tend to expand to the position shown in Fig. 2 and when the partition structure is forced downwardly into 90 the container body, the expansion of the cushioning elements to their effective position is completed by contact of the elements with the bottom 10 of the body and with the bottom edges of the transverse partition members 18. 95

It will be seen from Fig. 2 that the bottoms of the transverse partition members 18 are substantially straight and that they lie above the tops of the cushioning elements so 100 as not to interfere therewith, although the bottom edges of these partition members are substantially in contact with the tops of the cushioning elements and hold the free edges of the elements down in proper position 105 when the filler is being expanded and placed in the body. In Fig. 5 there is shown a slightly modified construction which may be otherwise identical with the construction shown in Fig. 2 except that the transverse partition members 18 are provided with V-shaped downward extensions 18a fitting somewhat loosely into the space between the inclined portions 20 and 21 of the cushioning elements. 110

Such extensions aid somewhat in opening 115 the cushioning elements to proper position from a collapsed position. It is obvious that as the partition structure is erected from collapsed position, the extensions 18a on the partitions 18 will contact with the outer 120 oblique surfaces 20 of the cushioning elements and will act as cams tending to force these surfaces outwardly to their fully effective position.

When the partition structure and cushioning elements are in their normal effective position, eggs may be dropped rapidly into the compartments and the lower ends of the eggs will be cushioned by the surfaces 20 and 21 125 with which they will contact. Thus the eggs 130

will be supported somewhat resiliently above the bottom 10 of the container, because the cardboard or other material of which the cushioning elements are constructed is slightly resilient or springy. Since the container is thus provided with a self contained cushioning element it is not necessary to provide a cushion upon which to rest the container while the eggs are being packed therein. 10 Also, when a number of such containers are piled in a crate, a cushion is not necessary at the bottom of the crate or between successive layers of containers.

The cushioning elements stiffen the whole 15 container and make crushing thereof more difficult. As has already been mentioned, the ends of the cushioning elements are substantially in contact with the ends 12 of the container and thus act as columns tending to 20 prevent inward crushing of the ends. The weight of the eggs on the cushioning elements tends to hold the cushioning elements against displacement so that these elements, in turn, hold the partition members 15, 16, and 17 25 against displacement and tend to prevent transverse crushing of the container. Also the fact that the partitions are stiffened somewhat by the cushioning elements makes these 30 partitions less likely to buckle and thus provides additional resistance against downward or vertical crushing of the container.

It is to be noted especially that this desirable cushioning construction does not interfere in any way with the folding or collapsing 35 of the container, but is perfectly adapted to a collapsible construction. As is customary in the carton trade, the supplies of containers will be shipped from the factory to the egg packers in collapsed or knocked-down 40 form, and the egg packers will first open or erect a container body, then open or erect a filler or partition structure, and then insert the erected filler in the body, which automatically positions the cushioning elements in 45 proper relation so that the container is ready to receive eggs.

Although the construction has been described with particular reference to eggs, it is obvious that this desirable cushioning arrangement is equally useful in connection 50 with any other fragile articles such as glass ware, or articles which should not be bruised, such as delicate fruit.

While certain embodiments of the invention 55 have been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A container comprising a body having 65 a bottom, a removable partition structure

for subdividing said body into a plurality of compartments, said partition structure including a plurality of partition members spaced a substantial distance from each other when in normal position in said body and 7 collapsible by moving longitudinally with respect to each other to a position adjacent each other when said partition structure is removed from said body, and a cushioning element secured to one of said partition members and removable from said body as a unit with said partition structure and extending in a generally transverse direction toward another partition member when said partition structure is in said body, to support an 8 article placed in said body above the floor thereof, said cushioning element being collapsible as a unit with said partition structure when said partition members are removed from said body and collapsed, and said other 9 partition member being movable longitudinally with respect to said cushioning element to permit collapse of the partition structure.

2. A container comprising a body having a bottom, a plurality of removable partition members placeable in said body in spaced relation to each other to form an article receiving space between them, and a substantially V-shaped cushioning element extending between two partition members with the 91 bottom of said element substantially resting upon the bottom of said body, one edge of said element being attached to one of said partition members, the other edge of said element being free to move longitudinally 95 with respect to the other partition member, said partition members and cushioning element when removed from said body being collapsible to occupy a relatively thin space.

3. A container comprising a body having a bottom, a plurality of removable partition members placeable in said body in spaced relation to each other to form an article receiving space between them, and a substantially V-shaped cushioning element extending between two partition members with the 10 bottom of said element substantially resting upon the bottom of said body, one edge of said element being attached to one of said partition members, the other edge of said element being substantially in contact with but 11 free from another one of said partition members, said partition members when removed from said body being collapsible by moving longitudinally relative to each other and 12 transversely toward each other, and said V-shaped element being folded up between said partition members by contact therewith when said members are collapsed.

4. A container comprising a body having a bottom, a plurality of removable partition members placeable in said body in spaced relation to each other to form an article receiving space between them, and a substantially M-shaped cushioning element extending 130

- ing between two partition members with the bottom edges of the side portions of said element substantially resting upon and supported by the bottom of said body, one of 5 such side portions being attached to one of said partition members, said partition members and cushioning element when removed from said body being collapsible to occupy a relatively thin space.
- 10 5. A container comprising a body having a bottom, a plurality of removable partition members placeable in said body in spaced relation to each other to form an article receiving space between them, and a substantially 15 M-shaped cushioning element extending between two partition members with the bottom edges of the side portions of said element substantially resting upon and supported by the bottom of said body, one of 20 such side portions being attached to one of said partition members, the opposite side portion of said element being substantially in contact with but free from another one of said partition members, said partition 25 members when removed from said body being collapsible by moving longitudinally relative to each other and transversely toward each other, and said M-shaped element being folded up between said partition 30 members by contact therewith when said members are collapsed.
6. A container comprising a substantially rectangular body having a bottom, a plurality of removable partition members placeable in said body, said partition members including an intermediate longitudinal member, a longitudinal member on each side of and spaced from said intermediate member, and a plurality of spaced transverse members 35 crossing said longitudinal members to for article receiving compartments in the interstices between said members, and a cushioning element between said intermediate longitudinal member and said longitudinal members on each side thereof for supporting articles resiliently above the bottom of said box, said cushioning element comprising a strip of material extending longitudinally below the bottoms of said transverse members and foldable transversely about a substantially longitudinal hinge axis to permit said partition members to be collapsed when removed from said body.
7. A container comprising a body, a partition structure placeable in and removable from said body, said structure comprising a longitudinal partition member and a plurality of transverse partition members to subdivide said body into a plurality of article receiving compartments, and cushioning means comprising a piece of sheet material folded around the lower edge of said longitudinal partition member and affixed thereto and extending in a general lateral direction from both sides of said member to provide a cushioning support for articles placed in said compartments.
8. A container comprising a body, a partition structure placeable in and removable from said body, said structure comprising a longitudinal partition member and a plurality of transverse partition members to subdivide said body into a plurality of article receiving compartments, and cushioning means comprising a piece of sheet material folded 70 around the lower edge of said longitudinal partition member and affixed thereto and forming a substantially V-shaped cushioning element on each side of said member to support articles placed in compartments on either side of said longitudinal partition member, each of said cushioning elements being transversely foldable to a collapsed position when said partition structure is removed from said body.
9. A container comprising a body having a bottom, partition means for subdividing said body into a plurality of compartments, said partition means including a partition member extending in one direction and a plurality of partition members extending in another direction, and a cushioning member attached to said member extending in one direction at a point above the bottom thereof, said cushioning member passing beneath 85 said partition members extending in another direction and extending obliquely downwardly from the member to which it is attached and resting on said bottom of said body at a point spaced from said member to 90 which it is attached.
10. A container comprising a body having a bottom, a removable and collapsible partition structure for subdividing said body into a plurality of compartments, said partition 95 structure including a partition member extending in one direction and a plurality of partition members extending in a direction transverse thereto, and a cushioning member secured to said first named partition 100 member for removal and insertion as a unit with said partition structure, said cushioning member having a portion passing beneath said transverse partition members and extending obliquely downwardly from a 105 point intermediate the top and bottom of said partition member to which it is secured and resting loosely upon said bottom of said body at a point spaced from said partition member to which it is secured, when 110 said partition structure is in normal erected position within said body, said obliquely extending portion of said cushioning member being folded to a position substantially parallel to the partition member to which it is 115 secured when said partition structure is removed from said body and collapsed.
11. A container for fragile articles comprising a body having a bottom, a partition member insertable in and removable from 120
- 125

said body, and a cushioning member of sheet material comprising a portion relatively permanently attached to a side of said partition member and another portion hingedly se-
5 cured to said attached portion at a point intermediate the top and bottom of said partition member and extending thence oblique-
ly downwardly and outwardly away from
10 said partition member to rest loosely on said bottom at a point spaced from said partition member when said partition member is in normal inserted position in said body.
